DESIGN FOR A LIQUID SOAP DISPENSER

Arthur L. Bobrick, Los Angeles, Calif.

Application September 16, 1940, Serial No. 95,092

Term of patent 14 years

To all whom it may concern:

Be it known that I, Arthur L. Bobrick, a citizen of the United States, residing at Los Angeles, in the county of Los Angeles and State of California, have invented a new, original, and ornamental Design for a Liquid Soap Dispenser, of which the following is a specification, reference being had to the accompanying drawing, forming part thereof.

In said drawing:

Fig. 1 is a perspective view of a liquid soap dispenser showing my new design;

Fig. 2 is a side elevation;
Fig. 3 is a top plan view; and
Fig. 4 is an end elevation.

I claim:

The ornamental design for a liquid soap dispenser, as shown.

ARTHUR L. BOBRICK.
